UNITED STATES PATENT OFFICE.

ABRAM N. PASMAN, OF WATERBURY, CONNECTICUT.

FLUSH-VALVE.

1,300,865.

Specification of Letters Patent. Patented Apr. 15, 1919.

Application filed July 13, 1918. Serial No. 244,728.

To all whom it may concern:

Be it known that I, ABRAM N. PASMAN, a citizen of the United States, residing in Waterbury, in the county of New Haven and 5 State of Connecticut, have invented an Improvement in Flush-Valves, of which the following is a specification.

This invention relates to a flush valve adapted for use in conjunction with closets 10 and other similar places where at required times a predetermined quantity of water is used for flushing purposes. The invention more particularly relates to an improvement on that form of flush valve shown and described 15 in Letters Patent No. 1,225,352, granted May 8, 1917. In the type of flush valve covered by the Letters Patent aforesaid, the valve upon being raised to open the same is maintained in a raised or open position 20 by the action or pressure of the flowing water or other medium against a vane or a plurality of vanes movably connected with the valve and adapted to bear against a portion of the tubular valve body to accomplish 25 this result.

The present invention relates still more particularly to the form of the vane or vanes and the manner in which the same are movably connected to the valve and attached to 30 one another so as to move in unison and hence irrespective of the number of vanes to become substantially a unit, as will be hereinafter more particularly described.

In the drawing,

35 Figure 1 is a sectional elevation illustrating a flush valve embodying the present invention.

Fig. 2 is also a sectional elevation on an enlarged scale, illustrating the valve and the 40 parts associated therewith and showing the valve in an open position.

Fig. 3 is an inverted plan of the parts as shown in Fig. 2.

Fig. 4 is a sectional elevation on a still 45 larger scale illustrating the valve and the parts associated therewith, and

Fig. 5 is a front elevation of one of the vanes which is movably connected to the valve member.

50 Referring to the drawing, 10 indicates a tank or other reservoir which is commonly employed with flush valves of the general type to which this invention relates. The flush valve comprises a pipe fitting consisting of a flange 11 extending from the tubular body member 12 that extends upwardly

into the tank from the bottom thereof and also a screw-threaded body member 13 extending through an aperture provided therefor in the bottom of the tank. This fitting 60 is secured in position in the bottom of the tank by a nut 14 being turned down against the under surface of the tank on the screw threaded exterior of the body of the fitting or otherwise. Connected to the outer end of 65 the fitting is a flush pipe 15, the connection being made by means of a nipple 16. This flush pipe, as will be understood, extends to the closet or other place to be flushed.

The valve member of the apparatus pref- 70 erably comprises a ring 17 which is interiorly screw threaded and provided with a flange 18. Associated with the ring 17 is a cap 19 having a flange 20 which is of appreciably larger diameter than the flange 18. 75 Fitting over the ring 17 and lying between the flanges 18 and 20 is a washer or valve 21. A plug 22 having a square head 23 is adapted to be turned down in the ring 17 and by means of a flange on the plug, the cap 19 is 80 secured in position so that the washer or valve may be maintained between the flanges 18 and 20. In suitable positions in the flange 18 there are bosses 24 and connected to each of these bosses 24 is a blade. As illustrated 85 there are three bosses 24 and a corresponding number of blades indicated at 25, 26, 27. Also as shown, each of these blades at its upper or outer end is provided with a tongue 28 which is passed through an aperture provided therefor in the corresponding boss and turned down within the recess formed by the boss so as to secure the blade 90 in position. These parts assume an angle of 120° to each other and may be suitably secured to one another, and furthermore are of such a width as to fit and be movable within the tubular body member 12.

Associated with this valve and the blades connected therewith I employ a plurality of 100 vanes. As illustrated I have shown two of these vanes and they are similarly constructed in rights and lefts. Each vane comprises a wing 29 and a wing 30 made at the same angle to each other as the angle between 105 the blades. At its lower and inside edges the wing 30 is flanged as indicated at 31 so as to form a pocket between this flanged edge and the wings 29 and 30 of the vane. These vanes as illustrated are pivotally connected to the blade 27 as indicated at 32. They are 110 also pivotally connected by means of a link

33 which passes through a slot 34 in the blade 27 so as to permit the vanes to swing on their pivotal point 32. The link 33 as well as the pivot 32 may be made of small 5 hollow tubes provided at their extremities with suitable washers so as to permit an appreciable lateral movement of these vanes relatively to the blade 27. Furthermore the ring 29 of each vane may be dented as indicated at 35 providing on its outer surface a boss or projection adapted to engage with a hole 36 provided therefor in the blade 27 when the parts are in the position shown in 10 Figs. 2 and 4.

15 With this form of flush valve I preferably provide the pipe fitting with an offset indicated at 37 in which there is connected an overflow pipe 38 extending upwardly into the tank 10 a sufficient distance to determine 20 the place at which the water in the tank will overflow into the pipe 38. On this overflow pipe 38 is fitted a collar 39 secured in place thereon by a set screw 40 or otherwise. The collar 39 carries a bracket 41 which at its extremity is provided with an eye 42. A rod 43 passes through the eye 42 and is suitably connected in the plug 22 so as will be apparent, to limit the upward movement of the valve and the parts associated therewith 25 30 when the same are open.

The valve may be operated by means of a lever 44 pivoted adjacent one end as indicated at 45 in a bracket 46 suitably secured on the edge of the tank 10. At the end of 35 that portion of the lever 44 which extends over the tank, the same is connected by a chain 47 with the upper end of the rod 43, while at the opposite end of the lever 44 the same is provided with a pull chain 48.

40 The parts of this apparatus are in their normally closed positions as indicated in Fig. 1 and in the operation of the valve and the parts associated therewith the same are raised by pulling the chain 48 to swing the 45 lever 44 and raise the valve, the extent of the movement of the valve being limited by the eye 42 and the bracket 41 which act as a stop therefor. When the valve is raised to the position shown in Fig. 2, the water or 50 other medium in the tank 10 will flow by gravity through the pipe fitting and the pressure of the flowing water against the wings 30 of the vanes attached to the blade 27 will cause the ends 29' of the wings 29 55 to project beyond the upper ends of the tubular body member 12 so as to maintain the valve in an open position as long as the pressure is sufficient to support the valve. The vanes are connected, as hereinbefore described, not only to move in unison, but being flanged retard the flow of the water and hence increase the pressure to a greater extent than would otherwise occur. Further the bosses 35 fitting within the hole 36 tend 60 65 to some extent to retard the action of the

70 vanes in their return to the normal inoperative position and hence to retard and control the reseating of the valve against the upper end of the tubular body member which acts as a valve seat, thereby producing an even seating of the valve which is not sudden. Still furthermore, the vanes being so connected as to have an appreciable lateral play 75 relatively to the blade in which they are connected as well as because of the dents 35 are prevented through impurities in the water from becoming inoperative through adhering to the blades to which they are attached.

80 In order to eliminate friction, as far as possible, and to prevent water adhesion, in addition to the boss 35, I may provide the wing 29 with a boss 49, and the wing 30 with similar bosses 50 and 51.

85 I claim as my invention:

1. A flush valve apparatus comprising a tubular body member having a seat, a valve member adapted to bear against said seat, a plurality of vanes movably connected to said valve member so that pressure exerted against said vanes by a medium flowing through said body member causes a part of said vanes to bear against the tubular body member to maintain the valve in an open position, and means for connecting said vanes to cause them to act as a unit. 95

2. A flush valve apparatus comprising a tubular body member having a seat, a valve member adapted to bear against said seat, a pair of vanes movably connected to said valve member so that pressure exerted against said vanes by a medium flowing through said body member causes part of said vanes to bear against a portion of the body member to maintain the valve in an open position, and a link for connecting the said vanes to cause them to act as a unit. 105

3. A flush valve apparatus comprising a tubular body member having a seat, a valve adapted to bear against said seat, a plurality of blades connected to said valve and movable within said tubular body member, a plurality of vanes movably connected to the said blades so that pressure exerted against the said vanes by a medium flowing through the said valve member causes a part of said vanes to bear against a portion of the tubular body member to maintain the valve in an open position, and means for connecting said vanes to cause them to act as a unit. 110 115 120

4. A flush valve apparatus comprising a tubular body member having a seat, a valve adapted to bear against the said seat, a plurality of blades connected with the said valve and adapted to fit and move within said tubular body member, a pair of vanes pivotally connected to one of the said blades, so that pressure exerted against said vanes by a medium flowing through said body member causes a part of the said vanes to bear 125 130

against a portion of the tubular body member to maintain the valve in an open position, and a link connecting said vanes and moving in a slot in the blade in which the 5 vanes are pivotally connected for securing the said vanes to one another to cause them to act as a unit.

5. A flush valve apparatus comprising a tubular body member having a seat, a valve 10 member adapted to bear against the seat, a plurality of radially placed blades connected to the valve and movable within the said tubular body member, a plurality of angular vanes movably connected to one of 15 the said blades and each having ribs extending along its outer edges so that pressure exerted against the said vanes by a medium flowing through said body member causes a part of the said vanes to bear against a 20 portion of the body member to maintain the valve in an open position, and means for connecting said vanes to cause them to act as a unit.

6. A flush valve comprising a tubular 25 body member having a seat, a plurality of radially placed blades connected to said valve and movable within said tubular body member, a pair of vanes pivotally connected to one of said blades each having an out-

turned rib along its outer edges so that pressure exerted against said vanes by a medium flowing through said body member causes part of said vanes to bear against a portion of the body member to maintain the valve in an open position, and a link connecting said vanes and moving in a slot provided therefor in the blade to which the 30 said vanes are pivotally connected so as to cause the said vanes to act as a unit.

7. A flush valve apparatus comprising a 40 tubular body member having a seat and an offset portion, an overflow pipe secured in the opposite portion of the tubular body member, a valve, a plurality of radially placed blades connected to the valve, a pair of vanes 45 pivotally connected to one of said blades so that pressure exerted against said vanes by a medium flowing through said body member causes part of said vanes to bear against a portion of the body member to maintain 50 the valve in an open position, means for connecting the said vanes to cause them to act as a unit, and means attached to the said overflow pipe for determining the extent of movement of the valve and parts associated 55 therewith in opening the same.

Signed by me this 29th day of June, 1918.

ABRAM N. PASMAN.
